(57) **CLAIM**

The ornamental design for a product display shelf, as shown and described.

DESCRIPTION

FIG. 1 is a perspective view of the product display shelf according to the present invention;

FIG. 2 is a front view of the product display shelf shown in FIG. 1;

FIG. 3 is a rear view of the product display shelf shown in FIG. 1;

FIG. 4 is a right side view of the product display shelf shown in FIG. 1;

FIG. 5 is a left side view of the product display shelf shown in FIG. 1;

FIG. 6 is a top view of the product display shelf shown in FIG. 1; and,

FIG. 7 is a bottom view of the product display shelf shown in FIG. 1.

The broken lines in the figures are used to represent subject matter that forms no part of the claimed design.

Where the figures show the article broken away, the break lines are understood to indicate unclaimed length or width, and any portion of the article between the break lines forms no part of the claimed design.

The parallel diagonal shading lines in FIGS. 1, 2, and 3 at the front of the product display shelf indicate transparency.
